ATTORNEY

UNITED STATES PATENT OFFICE.

WILLIAM JAMES LANE, OF POUGHKEEPSIE, NEW YORK, ASSIGNOR TO THE LANE BROTHERS COMPANY, OF SAME PLACE.

DESIGN FOR A DOOR-PLATE FOR DOOR-HANGERS.

SPECIFICATION forming part of Design No. 31,930, dated December 5, 1899.

Application filed November 7, 1899. Serial No. 736,193. Term of patent 14 years.

To all whom it may concern:

Be it known that I, WILLIAM JAMES LANE, a citizen of the United States, residing at Poughkeepsie, in the county of Dutchess and State

5 of New York, have invented and produced a new and original Design for a Door-Plate for Door-Hangers; and I do declare the following to be a full, clear, and exact description of the same, reference being had to the accompanying sheet of drawings, forming a part thereof.

Figure 1 is a plan view of a door-plate for door-hangers, showing my new design. Fig. 2 is a side view.

15 As shown in the drawings, the leading or material feature of my design consists of an

oblong plate A, having an upwardly-bent portion B, flattened on the top C and having the slot E arranged in the upwardly-bent portion.

Having thus described my invention, what I claim, and desire to protect by Letters Patent, is—

The design for a door-plate for door-hangers as herein shown and described.

In testimony whereof I affix my signature in the presence of two witnesses.

WILLIAM JAMES LANE.

Witnesses:

G. H. SHERMAN,
CLARENCE SAYERS.
